(57) **CLAIM**

The ornamental design for a clamp head, as shown and described.

DESCRIPTION

FIG. 1 is a top perspective view of a clamp head.

FIG. 2 is a bottom perspective view of the clamp head of FIG. 1.

FIG. 3 is a front-end plan view of the clamp head of FIG. 1.

FIG. 4 is a right-side plan view of the clamp head of FIG. 1. The left-side plan view is a mirror image of the right-side plan view.

FIG. 5 is a rear-end plan view of the clamp head of FIG. 1.

FIG. 6 is a top plan view of the clamp head of FIG. 1; and, FIG. 7 is a bottom plan view of the clamp head of FIG. 1.
